UNITED STATES PATENT OFFICE

99,888

DESIGN FOR A COMBINED WASHING MACHINE CASING AND WRINGER

John R. Morgan, Oak Park, Ill., assignor to Sears, Roebuck and Co., Chicago, Ill., a corporation of New York

Application April 4, 1936, Serial No. 61,944

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Combined Washing Machine Casing and Wringer, of which the following is a specification, reference being had to the accompanying drawing, forming a part thereof.

The drawing is a perspective view of a com-

bined washing machine casing and wringer, embodying my new design.

The side of the device opposite to that shown in the drawing is substantially similar to the side which is shown.

I claim:

The ornamental design for a combined washing machine casing and wringer, as shown and described.

JOHN R. MORGAN.
